UNITED STATES PATENT OFFICE.

ADOLPH GONTARD, OF MOCKAU, NEAR LEIPSIC, SAXONY, GERMANY.

EVAPORATING AND COOLING APPARATUS.

SPECIFICATION forming part of Letters Patent No. 254,003, dated February 21, 1882.

Application filed January 6, 1882. (No model.)

To all whom it may concern:

Be it known that I, ADOLPH GONTARD, a subject of the King of Saxony, residing at Mockau, near Leipsic, Saxony, German Empire, have invented certain new and useful Improvements in Evaporating and Cooling Apparatus, also applicable to other purposes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to an improved method and means for inspissating or evaporating liquids or liquid solutions.

The invention consists essentially in the use of a series of thin metallic (preferably copper) disks or thin disks made of porcelain, delft, or analogous ware, according to the nature of the liquid to be evaporated or the chemical constituents of the solution to be inspissated, said disks being provided with annular spiral or radial corrugations to increase their evaporating-surface without increasing their diameter, and mounted on a supporting-shaft, so as to form an endless or Archimedean screw.

The invention further consists in forming in the disks a radial slot extending from the central aperture to the periphery and increasing in diameter from the former to the latter point, whereby said disks may be mounted upon a shaft in the form of an endless or Archimedean screw by simply twisting the same after being slipped on the shaft and securing them into position.

It is a well-known fact that when a liquid is exposed to an evaporating medium or agent, be it fuel, hot or atmospheric air, or gases, the evaporation increases in proportion to the increase of the evaporating-surfaces and the volume of liquid upon such surfaces. If, therefore, a liquid is exposed to the evaporating medium in the form of a thin film and upon extended surfaces, the evaporation is accelerated in proportion to the surfaces so exposed and the depth of the film. It is upon this prin-

ple that my invention is based, and I accomplish the desired result by means of series of disks partly immersed in the liquid and caused to rotate therein. In this manner a portion of the liquid is continuously carried above the level of the bulk thereof, and in the thinnest possible film and exposed to the action of the evaporating medium, thus vastly increasing the superficial evaporating-surface of the apparatus in which these disks or blades are employed. For example, let us take a vessel of one square meter in cross-section, having therefore one square meter of evaporating-surface. If I apply to this vessel a series of ten disks or blades having an evaporating surface of 0.8 square meter (counting both sides) when about half immersed in the liquid, I increase the evaporating-surface by eight cubic meters, or nine-fold. As will be seen, this increase in effective evaporating-surface is an enormous one.

In the accompanying four sheets of drawings I have illustrated the application of the means to various branches of the arts in which such may be used, though they are applicable to any of the other branches in which inspissation or evaporation is the objective point.

Figures 1 and 2, Sheet 1, illustrate in longitudinal and transverse sections, respectively, an apparatus in which the disks employed are set at an inclination to the shaft upon which they are mounted. Fig. 3, Sheet 1, shows in section a series of disks having concentric corrugations. Figs. 4 and 5, Sheet 1, show in elevation disks having radial and spiral corrugations, respectively. Fig. 6, Sheet 1, shows a disk having a radial slit, whereby it is adapted to be twisted, and a series of such mounted upon a shaft in the form of a spiral or Archimedean screw. Fig. 7, Sheet 1, shows a series of slotted disks mounted upon a shaft to form an Archimedean screw. Figs. 8 and 9, Sheet 1, are side and end elevations of a preserving kettle or vessel for household use. Figs. 10 and 11, Sheet 2, are a longitudinal section and end elevation of an apparatus for desiccating fecal matter. Figs. 12 and 13, Sheet 3, show an end and side elevation of a distillery apparatus; and Figs. 14 and 15, Sheet 4, are like

views of another arrangement of the same. Figs. 16 and 17, Sheet 3, show a longitudinal section and plan view of a brine-evaporating pan; and Fig. 18, Sheet 2, is a longitudinal section of a steam-boiler.

Like letters of reference are employed to indicate like parts wherever such may occur in the above figures of drawings.

In carrying out my invention I employ a series of disks, D, that are preferably made of some good conductor of heat—such as copper or iron—whenever the liquid to be inspissated or evaporated admits of their being used. When the liquid is of such a nature as to attack and corrode the metals described, or when the action of such metals would tend to deteriorate the product of the operation, then I employ any other suitable materials. Porcelain, delft, hard rubber, and in some cases even wood, can be advantageously employed. Whenever metal can be employed I prefer to do so, and I use in preference thin copper disks. To increase the vaporizing-surface of these disks D, they are provided with concentric, radial, or spiral or other corrugations, d, Figs. 3, 4, and 5. This construction materially increases the vaporizing-surface without increasing the diameter of the disks.

According to the nature of the liquid under treatment, the disks may be mounted upon the shafts S with their planes at right angles or inclined to the shaft, or they may be arranged in the form of an endless or Archimedean screw.

This arrangement is especially advantageous when the burning of the inspissated liquid is to be guarded against, or when the evaporation is effected in closed vessels, as in the generation of steam, or when it is desired to still further accelerate the evaporation by agitation of the liquid, as in the case of distilling from the mash or generating steam. The agitation of the liquid sets free the vapors as fast as they are generated, and in the case of steam-boilers or other closed vessels the rapid oxidation thereof or the incrustation is prevented.

It is evident that when a series of the described disks or of blades are slowly rotated in a liquid that portion thereof which is carried above the level of the liquid in a thin film and exposed to the vaporizing medium will be evaporated before the surface to which such film adheres is again immersed in the body of the liquid. In this manner the evaporation is carried on in a most rapid manner, as will be readily understood.

In vessels of oblong form several disk-shafts S may be employed, and they may be arranged so that the disks of one shaft will rotate between the disks of the adjoining shafts, as shown in Figs. 10, 16, and 17, and when set at an angle to or in the form of an Archimedean screw upon such shafts the liquid will be caused to travel continuously toward one end of the vessel. Thus the liquid in the corners C of such vessel is also agitated, (which would not be the case were the disks mounted upon the

shaft or shafts S with their planes at right angles thereto,) as shown in Figs. 1, 2, 10, 12, 13, 14, 15, 16, 17, and 18.

In Figs. 8 and 9 I have shown the disks applied to a household utensil for inspissating or evaporating fruit-juices or for making preserves. As shown, it may be mounted upon a suitable stand and heated by a kerosene or other lamp, or it may be constructed to fit upon a cooking-stove.

In Figs. 10 and 11 I have shown an apparatus for desiccating or evaporating fecal matter or sewage, and the apparatus is provided with a series of shafts S, carrying disks D, so arranged that the disks upon one shaft will rotate between the disks of the adjacent shafts. All the shafts S are driven from a single driving-pulley through the medium of toothed gearing. In such apparatus ammonia is carried over with the aqueous vapor, which may be recovered by means of sulphuric acid. For this purpose I provide a separate reservoir, R, at that point where the vapors pass into the chimney A. In this reservoir, which is partly filled with sulphuric acid, I also arrange a shaft, S', carrying disks D, wherein the ammonia is fixed by means of the sulphuric acid, and as a large proportion of aqueous vapors is absorbed by the acid I remove it from time to time by allowing it to flow into a well arranged at the chimney end of the combustion-chamber. In this well W is arranged a shaft, S'', that carries also a series of disks. By means of this arrangement the ammonia is recovered in the form of a sulphate.

In Figs. 12, 13, 14, and 15 I have shown the method and means applied to distilling and inspissating apparatuses. In the latter two figures I have also shown an arrangement of devices whereby the evaporation may be hastened by means of a strong draft of air during the process of filling the apparatus, which, like the still, is heated by a steam-jacket, the liquid being fed in the form of a spray, and by injecting steam into the flue-pipe a strong draft is produced, the air entering at the door L, and a partial evaporation effected by rotating the disk-shafts.

Figs. 16 and 17 show the devices applied to the usual brine or evaporating pan used in salt-works, and in Fig. 18 I have shown their application to steam-boilers.

As a result of the use of the evaporating-disks in generators for steam in vacuum-pans or brine-pans or analogous apparatus, I have found that the oxidation of the metal used in the construction of these apparatus is not so rapid as is the case otherwise. This I attribute to the constant movement of the liquid under treatment, as it prevents the adhesion to the metallic surfaces of the vapor bubbles. In steam-boilers I have also found that it does more or less effectually prevent incrustation.

I wish it to be understood that I do not desire to claim broadly the use of a series of disks partially immersed and arranged to rotate in

a liquid or solution intended for evaporation or inspissation, such being old and well known, my invention consisting essentially in the use of corrugated disks and disks having a radial slot extending from the central aperture to the periphery, as hereinbefore described, and as specifically set forth in the claims.

Having now described my invention, what I claim is—

- 10 1. The herein-described devices for evaporating liquids, which consist of a series of corrugated disks, D, mounted spirally upon a shaft, S, in combination with a suitable vessel for containing the liquid to be evaporated, in the contents of which said disks are partially immersed and caused to revolve, whereby the liquid is not only more rapidly evaporated, but

kept continuously moving from one end of the vessel to the other, as set forth.

2. The combination, with a supporting shaft, 20 of a series of disks, D, provided with a central aperture and a radial slot gradually increasing in diameter from the central aperture to the periphery of the disk, whereby said disks may be mounted upon the shaft in the form of 25 a spiral or Archimedean screw, substantially as and for the purpose specified.

In testimony whereof I affix my signature in presence of two witnesses.

ADOLPH GONTARD.
